6 Sheets-Sheet 6

This technical drawing illustrates a complex mechanical assembly, likely a component of a larger machine. The assembly is mounted on a base structure. Key components include:

- A vertical support structure on the left, featuring a horizontal plate (104) with a slot (111) and a vertical slot (112). A vertical rod (108) is attached to the plate, and a horizontal rod (115) is attached to the vertical rod.
- A central vertical rod (115) with a horizontal slot (119) at the top. A horizontal rod (106) is attached to this slot, and a vertical rod (107) is attached to the horizontal rod (106).
- A vertical rod (115) on the right, with a horizontal slot (119) at the top. A horizontal rod (116) is attached to this slot, and a vertical rod (117) is attached to the horizontal rod (116).
- A vertical support structure on the right, featuring a vertical rod (109) and a horizontal rod (114) attached to it.
- A base structure at the bottom, featuring a horizontal plate (103) with a slot (110) and a vertical slot (102). A horizontal rod (65) is attached to the base, and a vertical rod (107) is attached to the base.
- Curved rods (66) attached to the base structure.

THEATER

Application filed September 18, 1928. Serial No. 306,641.

The present invention relates to theaters, and is more particularly directed toward the provision of theatrical apparatus including movable scenery and stage settings, whereby continuous action may be maintained before the audience.

In the ordinary production of drama, comedy and the like in the theater, the action takes place on or in a number of stage settings each of which is set up or assembled on the stage at each performance. The entire setting is disassembled and stored away, and another complete setting then assembled on the stage. The curtain is lowered or the stage darkened while the scene shifting is taking place. The necessity of taking down one scene and moving it off the stage and then assembling another scene limits the production to one wherein the entire plot can be developed with a small number of scene changes; hence, this method of changing scenery has seriously limited the spoken drama to productions wherein the number of scene changes is small. Furthermore, it is impossible, with the present type of theatrical apparatus to produce continued action or change from one scene to the next. As the mechanics of scene changing requires the dropping of the curtain for a prolonged period in which the stage is kept in darkness, a considerable interval of time is consumed and the continuity of the action before the audience is to a large extent lost. The change is sudden and complete and to a large extent unnatural. In addition, the common method of theatrical display makes it necessary to take down and completely reassemble the same scene when parts of the performance presented at different times are to take place in the same setting.

According to the present invention it is possible to maintain continued action from one scene to the next without the necessity of lowering the curtain or without the darkened interval and also without waiting for the settings to be taken down or reset. The present invention contemplates the employment of preassembled complete stage settings so arranged and interrelated that any stage setting may be placed before the au-

dience and moved out of view of the audience while another pre-assembled stage setting is simultaneously brought into view. A number of stage settings sufficient for the performance are provided. They are preferably stored in the wings of the theater and any desired setting can be moved from the wing, in which it is stored, to place it before the audience and then returned to the wing so as to be ready for the next presentation.

The present invention contemplates the shifting of the scene or scenes back and forth behind the curtain line in full view of the audience. The stage settings may be made up to represent a complete room, an outdoor scene or the like, and as one scene is being withdrawn from the view of the audience another scene is being brought into view. The actors are able to pass from one scene to the next in full view of the audience so that the audience appears to see action transpiring from one room to another room, or from one stage setting to another stage setting.

According to the present invention, any two stage settings may be moved back and forth as desired so that action can take place in one or two rooms at a time, and the place of action can transfer back and forth between the rooms. It is possible, according to the present invention, to connect any one of a number of stage settings on one side of the theater with the stage setting which is being viewed by the audience, and to move the latter stage setting out of view and to bring into view the desired stage setting which has been coupled to it.

A further object of the present invention is to provide stage settings capable of carrying complete stage properties, and wherein the floor portions of the stage settings are made up in sections so that the floor portion may bend or flex, permitting it to be placed either in a horizontal position on the stage floor, or suspended in a vertical position in the wing of the theater. Where the scene employs an end or side wall, one of these walls is, according to the present invention, preferably permanently attached to the floor portion, and the floor portion suspended from this wall portion when the scene is

hoisted into the wing. The end or side wall is detachably connected with the movable floor portion.

The present invention also contemplates the provision of a flexible back or rear wall for settings requiring a back wall. It is brought on to the stage with the floor and side walls, and is coupled to the floor so as to move with the floor as the parts are drawn onto the stage. The jointed back wall is arranged so as to fold in the rear part of the wing of the theater. The parts or sections of the rear wall remain vertical, resting on the lower edges of the sections when being thus stowed away. The back wall is automatically stowed away when a setting is withdrawn into the wing. It may be left in this position, or may be manually placed elsewhere so that a different backwall may be substituted in case 20 the next scene drawn in from this wing requires such change.

Various attempts have been made to accomplish some of the foregoing objects by the use of stage settings which were moved bodily forward and backward on the stage, or from the wings into the center of the stage, or the entire scene has been elevated or lowered to bring another scene into view. These devices have never, so far as I am aware, been adopted. They all require special theater construction or greater space than is usually available. Schemes involving moving scenes forward and back or sidewise require excessive stage area, impossible to obtain in any ordinary theater. As a stage opening is from 28 to 34 feet wide, it would be necessary to have a building more than three times this width if scenes are to be moved onto the stage from either side. As the present invention 40 contemplates flexible stage settings which are stowed in collapsed condition, the movable stage settings may be accommodated in an ordinary theater where the wings are much narrower than the stage opening.

Other and further objects of the invention will be apparent as this description proceeds.

The accompanying drawings show, for purposes of illustrating the present invention, one of the many possible embodiments in which it may take form, together with modifications of certain parts, it being understood that the drawings are illustrative of the invention rather than limiting the 55 same.

In these drawings:

Figure 1 is a perspective view of a theater stage taken from the front with parts broken away, and showing one setting in place on the stage and another setting suspended in the wing, but connected to the first setting and in place to be brought into view of the audience;

Figure 2 is a diagrammatic plan of a theater stage;

Figure 3 is a perspective view of a system of cables and traveler suitable for scene shifting;

Figure 4 is a fragmentary sectional view through the floor portions and lower wall 70 portion of two adjacent stage settings;

Figure 5 is a perspective view looking at the rear of two stage settings and a corner of one of the settings;

Figure 6 is a fragmentary detail perspective view of a form of end or side wall adapted to be attached to the traveler;

Figure 7 is the perspective view of two stage settings in an intermediate position on the stage, showing a device for masking off the end portions of the stage settings;

Figure 8 is a perspective view of one form of action-sustaining property supporting floor suitable for use with these stage settings; and

Figure 9 is a perspective view somewhat similar to Figure 2 showing a different form of mechanism for operating the shiftable stage settings.

The present form of theatrical apparatus may be installed in a conventional theater. It is placed back of the curtain line and will occupy the stage floor, wings and back stage. The building will usually be provided with a permanent floor, but as this is not the 90 floor on which the action takes place, the floor need not be finished like the regular stage floor of a theater. The action takes place on a movable floor, and the operating mechanism for shifting the scenes includes a traveler adapted to move back and forth above the permanent stage floor.

A suitable form of operating mechanism is diagrammatically illustrated in Figure 3. The traveler is indicated at 10. It is connected to two ropes or cables 11 and 12 which pass about fixed pulleys 13. The ends of these ropes or cables are connected to a cross-head 14 disposed under the stage floor. The crosshead and traveler are held in parallelism by the ropes. This crosshead is adapted to be moved back and forth by tackle. As shown, this tackle consists of pulley blocks 15 and 16 connected to the crosshead 14, pulley blocks 17 and 18 anchored to some permanent part of the theater, and a rope or cable 19 threaded through all the blocks and coiled about a winding drum 21 which may be driven by a motor through suitable reduction gearing and clutch, not shown. As the 100 winding drum 21 is turned back and forth the traveler 10 will be shifted back and forth across the stage floor.

The crosshead 14 is also connected to cables 23 and 24 which pass about pulleys 25 underneath the stage floor and up into the wings 26 and 27 of the theater. As here shown each of these cables is adapted to operate two settings. The cables 23 and 24 are connected to rings or links 23' and 24' 110 115 120 125 130

which are connected to the various settings by cables 23a, 23b, 24a and 24b. These cables pass about pulleys and counterweight systems 28a, 28b, 29a and 29b, and the free ends 5 of the cables are connected to a portion of the scene to be operated. It will be apparent that the arrangement of cables is such that the scene connected with the rope 23a will be lowered as the traveler 10 is moved to the 10 right and that the scene connected to the cable 24a will be simultaneously hoisted. The settings connected to cables 23b and 24b are hoisted into the wing and tied up.

In Figures 1 and 3, the traveler 10 is indicated at the righthand side of the stage, while in Figure 2, it is indicated as being at the lefthand side of the stage. This traveler moves back and forth from one side of the stage to another, and is adapted to shift the 20 scenery so as to place either scene behind the proscenium arch, the complete scene being drawn into view from the right as indicated in Figure 1, or from the left as indicated in Figure 2. The traveler will move 25 back and forth behind the curtain line, indicated at 30 in Figure 2, guides (not shown) being employed to support the traveler.

In the form of construction shown in Figures 1 and 4, the traveler 10 is shown as having a bottom plate 10' and two vertical plates 10" spaced apart. The bottom plate is permanently connected to flooring 31, 32 extending to the right and the left. This flooring is made up of boards sufficiently 35 heavy to sustain the stage properties and actors and is supported on rollers 33 adapted to travel back and forth on a track 34 extending completely across the permanent stage floor of the theater. The ends of the track 40 connect with curved guide-ways 35 and 36 on the opposite sides of the theater adjacent to the side walls 37. The guide-ways 35 and 36 are adapted to guide the jointed floor 31 and 32 up on the side walls of the theater, 45 as indicated at the right in Figure 1. As the traveler 10 moves back and forth across the stage floor the portion of the flooring supporting a setting will move from the position where it is directly behind the proscenium 50 arch in a position to support the stage setting to the position indicated at the right of Figure 1 where it is stored on the floor and inside the wall of the wing of the theater. When it moves back, the portion stored adjacent 55 the side wall of the theater will be brought in front of the arch.

Various types of stage settings may be used on the movable flooring 31 and 32. These stage settings may be made up to represent 60 rooms, outdoor scenes, roof gardens and the like according to the production which is to be staged. Where the setting is to represent a room it will include a floor portion 40, side walls 41 and 42, a rear wall 65 43, a ceiling 44 and various stage properties

such as furniture, pictures, doors, windows and the like which are fastened to or built into the proper parts of the stage setting. Where the stage setting is to represent an outdoor scene, the setting will include the floor portion, and may include side walls or back walls according to the scene being represented. 70

In some cases, the side and back walls will take the form of curtains painted to represent the desired background. All the stage properties which are to rest on the floor or hang on the walls during the showing of the scene are preferably fastened to the floor or wall in the position they are to occupy. Additional movables may be placed on the floor without fastening. Such properties are removed before the same is hoisted into the wing. 75

Where the double thickness movable floor 80 is to be employed, the upper floor may be made of a heavy carpet, suitably reinforced, or it may be made of strips of multiple ply veneer 40a secured to the carpet or floor covering 40b, as shown in Figure 4. A modified 85 form of floor is shown in Figure 7. It comprises thin metal straps 45 hinged together at 46. The floor covering, such as a carpet 47, is placed on top of these straps and the space between the straps is filled in with 90 cork or other sound-deadening material 48. The floor portions 40 of the stage settings are adapted to be fastened to the movable floors 31 and 32 by means of tongues 49 adapted to fit into grooves 50 in the flooring 100 31 and 32 as indicated in Figure 4.

The wall portion 42 adjacent the traveler 10 is fastened to the traveler by means of straps 51 which extend down between the channel walls 10" of the traveler. The other 105 side walls may be provided with doors, and articles of furniture such as indicated at 53 may be fastened to the side walls.

The ceiling 44 is suspended from above by cables indicated at 44'. This ceiling preferably is somewhat longer than a scene setting and extends beyond the setting into the wings, as indicated, so as to provide a ceiling for the portion of the setting being brought into view or taken from view. The 110 weight of the ceiling is preferably taken by the ropes which support it so that it does not rest on the movable walls of the settings. 115

The upper end of the side wall 41 is connected with the cable 23 which acts on the side wall and floor portion of the setting to raise them into the wing where they remain suspended until again used. These cables pass underneath the ceiling ends as indicated in Figures 1 and 3. 120

The back wall 43 of the setting is jointed as indicated at 43' and is detachably fastened to the side walls 41 and 42 as indicated in Figure 5. Various forms of construction may be used for fastening these wall parts 130

together. As here indicated, the side wall 42 is provided with rearwardly extending pins 54 adapted to extend out behind the rear wall 43. Clamping lugs 55 are adapted to be 5 swung down onto these pins to come behind the heads of the pins. The side wall 41 and the back wall 43 is fastened together by means of spring catches 56, adapted to engage lugs 57 having bevelled faces 58. The 10 floor carries a rearwardly extending pin 59 to enter a slot 60 in the back wall 43. These connections insure the moving of the side and back walls of the setting along with the floor of the setting.

15 In Figure 1, one complete stage setting is shown as being in place on the stage and a second stage setting is shown on the right-hand side being ready to be shifted into view. This stage setting in the right wing consists 20 of a floor portion 40', side wall 42', and end wall 41', which may be constructed about the same as the stage setting shown in the center of the figure. The floor portion of this stage setting is fastened to the movable floor 32 25 and the upper edge of the wall 41' is connected to the cable 24. If one desires to shift the scene which is already in view and bring on the other scene, it is merely necessary to manipulate the cable system. This will start 30 both sets toward the left as indicated in Figure 1 and will cause the movable floors 31 and 32 and both stage settings to move toward the left. The lower movable floor will come down along the guide 36 and pass up 35 along the guide 35. The side wall 41 will pass out beyond the end of the ceiling 44 and then be lifted up by the cable 23a, the lugs 57 being carried up beyond the catches 56 so as to disconnect the side wall 41 from the 40 rear wall 43.

This rear wall will pass along the floor and a guide 65 and toward the wing until it is brought against a stationary curved guide 66 which will cause the back wall 43 to collapse or fold along the vertical joints as indicated in Figures 2 and 7. The back wall will, of course, be disconnected from the floor and side wall 42. The folded back will 45 rest on its lower edge until it is again to be used, or until moved away to make room for another back wall. When a back wall is to be brought into view, it is coupled to the movable setting and is drawn on simultaneously with it.

50 During the motion of the stage settings, actors may pass through a doorway in the walls 42 and 42' and pass from one room or setting into another. This action takes place before the audience while the stage settings 55 are moving and gives the audience the illusion of movement of the actors. One complete stage setting is taken out of view of the audience and another complete stage setting brought into view.

55 In order that the oncoming and disappear-

ing portions of the stage settings may be hidden from the view of the audience, curtains or teasers 67 are provided adjacent the ends of the ceiling, and these curtains are dropped down over the setting as soon as the setting 70 is moved beyond the end of the ceiling so that the audience cannot look beyond a pre-determined point. They are raised just before the side wall is to come into view. These teasers or curtains may be operated by a cable 68, either by hand or by suitable connection with the motor driven cable system shown in Figure 3.

When the performance is one requiring more than two scenes, additional settings 80 similar to those which have been described may be used. Figure 3 shows an arrangement of four settings, the two additional settings being indicated at 70 and 71. They are connected with the cables 23b and 24b 85 and when not in use are tied up in the wing by cables 72 and 73'. The counterweights in the cable system keep everything taught. When the settings are to be changed, the new one is lowered and fastened to the traveler 90 and the other setting hoisted and tied in elevated position.

In the modified form of construction illustrated diagrammatically in Figure 9, the entire operating mechanism for shifting the 95 scenery is placed above the stage. Here the reciprocating traveler 110 is connected to cables 101 and 102 which pass about guide pulleys 103 and are connected to pulley blocks 104 and 105. A cable 106 is wound 100 about a winding drum 107 and passed through stationary pulley blocks 108 and 109 and to movable pulley blocks 104 and 105. The cable and pulley blocks are arranged so that when the drum 106 is turned 105 in one direction, the traveler 110 moves to the right and when turned in the other direction the traveler moves to the left.

The upper ends of two settings in the right wing are indicated at 111 and 112. 110 These settings are connected to cables 114 and 115 which pass about fixed pulleys and support counterweights 116 and 117. The other end of these cables is fastened to the pulley block 105. Two other stage settings 115 may be placed in the left wing and connected by similar cables to the pulley block 104. For simplicity these are omitted from the drawings. This counterweight system with ropes and cables serves to move the 120 setting on one side up as the one on the other side is lowered. The teasers or curtains used to cut off the view of the audience from the wings of the theater are operated by levers indicated at 118. These are under 125 the control of cords 110 wound about the shaft of the winding drum 107. This winding drum is operated by suitable motor gearing and clutches so as to move the scenery back and forth.

Comparatively little power is required for effecting changes of stage settings. This is on account of the employment of a substantially balanced system. Furthermore, 5 the scene shifting is accomplished to a large extent by a push or pull exerted by the traveler. The hoisting of the setting does not take place all at once, as the portion of the setting on the movable floor is pushed 10 toward the wing by the traveler.

Where the stage setting is to embody an outdoor scene, the ceiling will of course be hoisted out of view. It will be particularly noted that the present type of movable stage 15 setting adapts itself for use in existing theaters wherein the wings are much smaller than the width of the stage. The ability to fold and store the stage settings in a restricted space makes it possible to install 20 the present type of shiftable stage settings in the ordinary theater.

It is obvious that the invention may be embodied in many forms and constructions, and I wish it to be understood that the particular form shown is but one of the many forms. Various modifications and changes being possible, I do not limit myself in any way with respect thereto.

What is claimed is:

1. The combination with a theater having a permanent stage, proscenium arch in front of the stage, and wings to each side of the stage, of a scene shifting traveler supported on the permanent stage and guided 25 for movement back and forth between the wings, and two preassembled stage settings each coupled to the traveler and movable thereby so that one setting or the other setting or adjacent portions of both settings are visible through the arch.

2. The combination with a theater having a permanent stage, proscenium arch in front of the stage, and wings to each side of the stage, of a scene shifting traveler supported 45 on the permanent stage and guided for movement back and forth between the wings, two preassembled stage settings each coupled to the traveler and movable thereby so that one setting or the other setting or adjacent portions of both settings are visible 50 through the arch, and means to prevent the audience from looking into the wings whereby the portions of the settings behind the wings are invisible.

3. The combination with a theater having a permanent stage, proscenium arch in front of the stage, and wings to each side of the stage, of a scene shifting traveler supported on the permanent stage and guided for 60 movement back and forth between the wings, and two preassembled stage settings each coupled to the traveler and movable thereby so that one setting or the other setting or adjacent portions of both settings are visible through the arch, the settings hav-

ing jointed floor portions permanently fastened together so that the settings may be folded behind the wings.

4. The combination with a theater having a permanent stage, proscenium arch in front of the stage, and wings to each side of the stage, of a scene shifting traveler supported on the permanent stage and guided for movement back and forth between the wings, two preassembled stage settings each 70 coupled to the traveler and movable thereby so that one setting or the other setting or adjacent portions of both settings are visible through the arch, the settings having jointed floor portions permanently fastened together so that the setting may be folded behind the wings, one of the settings having side walls and a jointed back wall separably connected with the floor and side walls, and means to fold the back wall as this setting 75 is moved into the wing.

5. The combination with a theater having a permanent stage, proscenium arch in front of the stage, and wings to each side of the stage, of a scene shifting traveler supported 80 on the permanent stage and guided for movement back and forth between the wings, two preassembled stage settings each coupled to the traveler and movable thereby so that one setting or the other setting or adjacent portions of both settings are visible 85 through the arch, the settings having jointed floor portions permanently fastened together so that the setting may be folded behind the wings, one of the settings having side walls and a jointed back wall separably connected with the floor and side walls, and means to fold the back wall as this setting is moved into the wing.

6. The combination with a theater having a permanent stage, proscenium arch in front of the stage, and wings to each side of the stage, of a scene shifting traveler supported on the permanent stage and guided for movement back and forth between the wings, two preassembled stage settings each 90 coupled to the traveler and movable thereby so that one setting or the other setting or adjacent portions of both settings are visible through the arch, the settings having jointed floor portions, and means to guide the floor portions upwardly behind the wings.

6. The combination with a theater having a permanent stage, proscenium arch in front of the stage, and wings to each side of the stage, of a scene shifting traveler supported on the permanent stage and guided for movement back and forth between the wings, two preassembled stage settings each 100 coupled to the traveler and movable thereby so that one setting or the other setting or adjacent portions of both settings are visible through the arch, the settings having jointed floor portions, and means to guide the floor portions upwardly behind the wings.

7. The combination with a theater having a permanent stage, proscenium arch in front of the stage, and wings to each side of the stage, of a scene shifting traveler supported on the permanent stage and guided for movement back and forth between the wings, two preassembled stage settings each 110 coupled at their adjacent ends to the traveler and movable thereby so that one setting or the other setting or adjacent portions of both settings are visible through the arch, and flexible loops each connected to the carrier and to the opposite ends of a corresponding setting, each loop passing over guides above the corresponding wing, each setting having a flexible floor, the floor bending and being 115

carried up by the loop attached to it as the setting is shifted out of view.

8. The combination with a theater having a permanent stage, proscenium arch in front of the stage, and wings to each side of the stage, of a scene shifting traveler supported on the permanent stage and guided for movement back and forth between the wings, two preassembled stage settings coupled to the traveller on opposite sides thereof, said settings each having flexible floor jointed so as to permit the floor to lay flat on the stage or bend so that it may pass from the stage into a vertical plane behind the wings to be supported from above, pulleys carried in the tops of the wings, ropes connected to the remote ends of the settings and carried around the pulleys, and connected to the traveler whereby the settings are movable with the traveler to present one setting or the other setting, or portions of both settings in position for viewing through the arch, the invisible portions of the setting being stowed behind the corresponding wing.

9. The combination with a theater having a permanent stage, proscenium arch in front of the stage, and wings to each side of the stage, of a scene shifting traveler supported on the permanent stage and guided for movement back and forth between the wings, two preassembled stage settings each coupled at their adjacent ends to the traveler and movable thereby so that one setting or the other setting or adjacent portions of both settings are visible through the arch, flexible loops each connected to the carrier and to the opposite ends of a corresponding setting, each loop passing over guides above the corresponding wing, each setting having a flexible floor, the floor bending and being carried up by the loop attached to it as the setting is shifted out of view, at least one of the settings having a detachable foldable back wall, and means to support the back wall on the stage floor behind the wing.

10. The combination with a theater having a permanent stage, proscenium arch in front of the stage, and wings to each side of the stage, of a scene shifting traveler supported on the permanent stage and guided for movement back and forth between the wings, two preassembled stage settings each coupled to the traveler and movable thereby so that one setting or the other setting or adjacent portions of both settings are visible through the arch, and teasers for masking the portions of the settings beyond the sides of the arch.

11. The combination with a theater having a permanent stage, proscenium arch in front of the stage, and wings to each side of the stage, of a scene shifting traveler supported on the permanent stage and guided for movement back and forth between the wings, a plurality of preassembled stage settings, any two of which may be coupled to the traveler

and movable thereby so that one setting or the other setting or adjacent portions of both settings are visible through the arch, and teasers for masking the portions of the settings beyond the sides of the arch, said settings having end walls which render the wings invisible to the audience when the entire setting is being viewed, whereby one setting may be detached from the traveller and another setting attached to it.

12. The combination with a theater having a permanent stage, proscenium arch in front of the stage, and wings to each side of the stage, of a scene shifting traveler supported on the permanent stage and guided for movement back and forth between the wings, a stage setting coupled to one side of the traveler and including a flexible floor, a side wall at the remote end of the floor, a side wall above the traveler, and stage properties carried by the floor and walls, a stage setting coupled to the other side of the traveler, the settings being movable with the traveler so that one setting or the other setting or both settings are visible through the arch, and means connected with the traveler and simultaneously operable therewith for hoisting the remote side wall and floor after these portions of the setting have passed by the arch.

13. The combination with a theater having a permanent stage, proscenium arch in front of the stage, and wings to each side of the stage, of a scene shifting traveler supported on the permanent stage and guided for movement back and forth between the wings, a stage setting coupled to one side of the traveler and including a flexible floor, a side wall at the remote end of the floor, a jointed back wall extending upwardly from the floor, a side wall above the traveler, stage properties carried by the floor and walls, a stage setting coupled to the other side of the traveler, the settings being movable with the traveler so that one setting or the other setting or both settings are visible through the arch, means connected with the traveler and simultaneously operable therewith for hoisting the remote side wall and floor after these portions of the setting have passed by the arch, and means to guide the back wall rearwardly separated from the floor and end walls.

14. The combination with a theater having a permanent stage, proscenium arch in front of the stage, and wings to each side of the stage, of a scene shifting traveler supported on the permanent stage and guided for movement back and forth between the wings, a stage setting coupled to one side of the traveler and including a flexible floor, a side wall at the remote end of the floor, a side wall above the traveler, stage properties carried by the floor and walls, a stage setting coupled to the other side of the traveler,

the settings being movable with the traveler so that one setting or the other setting or both settings are visible through the arch, and means connected with the traveler and 5 simultaneously operable therewith for hoisting the remote side wall and floor after these portions of the setting have passed by the arch, and teasers to mask the portions of the settings beyond the arch so that the disposition thereof is invisible.

15. In a theater, two stage settings arranged in tandem and connected to a traveler, means to shift the traveler laterally across the stage, and hoisting means operable with the traveler and connected with the outer ends of each setting for hoisting the setting as the setting is moved outwardly.

16. In a theater, two stage settings each arranged to represent a room having a floor 20 and side and back walls movable across the stage, a traveler, the adjacent ends of the floor portions of the settings being attached to the traveler, the adjacent side walls being detachably attached to the traveler, the outer 25 side walls being hingedly attached to the corresponding floor portion, and means to hoist an outer side wall and floor portion of one setting while the corresponding parts of the other setting are being brought onto the 30 stage.

17. In a theater, two stage settings each arranged to represent a room having a floor and side and back walls movable across the stage, a traveler, the adjacent ends of the 35 floor portions of the settings being attached to the traveler, the adjacent side walls being detachably attached to the traveler, the outer side walls being hingedly attached to the corresponding floor portion, and means to hoist 40 an outer side wall and floor portion of one setting while the corresponding parts of the other setting are being brought onto the stage, the back wall being in the form of hinged sections detachably connected to the 45 floor portion and side walls, and means for disconnecting the back wall from the outer side wall and the outer portion of the floor when moved away from the stage.

18. In a theater, a stage setting comprising 50 a flexible action sustaining floor, stage properties attached to the floor, and means to manipulate the stage setting as a unit to shift it from a position wherein it is visible through the proscenium arch to a position wherein it is suspended in the wing.

19. In a theater, a stage setting comprising 55 a flexible action sustaining floor, stage properties attached to the floor, an end wall attached to the floor, and means to manipulate the stage setting as a unit to shift it from a position wherein it is visible through the proscenium arch to a position wherein it is suspended in the wing, the floor being suspended from the end wall.

60 20. In a theater, a pair of stage settings

each comprising a flexible action sustaining floor and stage properties attached to the floor, and means to manipulate both stage settings as units to shift one from a position wherein it is visible through the proscenium arch to a position wherein it is suspended in the wing, and to bring the other from the opposite wing to visible position in front of the arch.

21. In a theater, a plurality of preassembled stage settings each including a flexible action sustaining floor, and means to move each setting laterally across the stage floor, the setting bending so that it may pass up or down the wing.

22. In a theater, a stage, two preassembled stage settings each including a jointed action sustaining floor, and scene shifting mechanism to which each setting is jointed, the settings being so related that when one setting is moved across the stage to remove it from view, the other setting is simultaneously brought into view.

23. A stage setting having a laterally shiftable floor, side walls secured to the floor, and a vertically jointed back wall detachably secured to the floor to move therewith and extending the entire length of the setting, the back wall being detachably secured to the side walls of the setting.

24. In a theater, the combination with a stage floor of a preassembled stage setting having a transversely jointed action-sustaining floor, means to bodily shift the setting laterally, the floor portion of the setting folding about the transverse joints, and means to hoist the floor so that the setting may be stored in a space narrower than the length of the setting.

25. A stage setting having a transversely jointed action-sustaining floor, side walls one of which is detachably connected to the floor, the other hingedly connected with the floor, and means to laterally shift the entire setting off a stage and to hoist the hingedly connected side wall and jointed floor so that they are suspended to one side of the stage.

26. A theater having a permanent stage, a proscenium arch in front of the stage, wings to the sides of the arch, each wing being substantially narrower than the arch, a preassembled collapsible stage setting adapted to rest on the permanent stage and extend from one side of the arch to the other, and means to move the setting laterally into the wing, the portion of the setting in front of the arch being moved laterally only, the portion in the wing being moved laterally and vertically to lift it up after it passes the side of the arch.

27. A theater having a permanent stage, a proscenium arch in front of the stage, wings to each side of the stage, a transversely jointed floor supported for lateral movement across the stage, the length of the floor being at least twice the width of the arch,

and a traveler to which the center of the floor is connected, the traveler being capable of shifting the flexible floor so that either half thereof is behind the arch, the other half being stored in the wing and extending up the side wall of the wing.

28. A theater having a permanent stage, a proscenium arch in front of the stage, wings to each side of the stage, a transversely jointed floor supported for lateral movement across the stage, the length of the floor being at least twice the width of the arch, a traveler to which the center of the floor is connected, the traveler being capable of shifting the flexible floor so that either half thereof is behind the arch, the other half being stored in the wing and extending up the side wall of the wing, a plurality of pre-assembled stage settings, means to suspend certain settings in the left wing and other settings in the right wing, the settings having flexible floor portions capable of being connected with the jointed floor adjacent the traveler, and means to synchronously move the traveler and raise one setting while lowering the other setting so that settings may be successively brought in front of the arch, first from one side and then from the other side.

29. A theatrical stage having a permanent stage, proscenium arch in front of the stage, and wings to each side of the stage, a traveling stage guided for back and forth movement between the wings, and a plurality of stage settings assembled on the traveling stage and movable therewith so that one setting or adjacent portions of several settings are visible through the arch.

30. A theatrical stage having a permanent stage, proscenium arch in front of the stage, and wings to each side of the stage, a traveling stage guided for back and forth movement between the wings, and a plurality of stage settings assembled on the traveling stage and movable therewith so that one setting or adjacent portions of several settings are visible through the arch, each stage setting comprising a flexible floor and stage properties secured to the flexible floor.

31. A theatrical stage having a permanent stage, proscenium arch in front of the stage, and wings to each side of the stage, a traveling stage guided for back and forth movement between the wings, a plurality of stage settings assembled on the traveling stage and movable therewith so that one setting or adjacent portions of several settings are visible through the arch, and means to hoist the invisible portions of a stage setting into the upper part of the adjacent wing.

32. In a theater, a preassembled stage setting having a foldable floor on which stage properties normally resting on a stage floor are permanently secured in predetermined fixed positions, a movable traveler, and

means to secure the floor of the stage setting to the traveler so that the entire setting including the properties may be moved as a unit.

33. In a theater, a plurality of preassembled stage settings arranged for storage in the opposite wings of the theater, each setting having transversely jointed foldable floor portions on which stage properties normally resting on a stage floor are permanently secured in predetermined fixed position, a movable traveler and quick-detachable means to secure two entire stage settings to the traveler, the settings being taken from opposite wings and secured thereto as complete units.

34. In a theater, a stage area, a stage opening in front of the stage area for viewing a stage setting and action taking place thereon, two collapsible stage settings bearing stage properties and capable of supporting actors, the settings being arranged in tandem and connected together, and stage setting shifting and collapsing means for shifting the stage settings laterally across the stage area in either direction so that one setting or the other setting or adjacent portions of both settings are visible through the stage opening and for automatically collapsing either setting into a space at the side of the stage opening of less horizontal dimension than the length of the setting when such setting is removed from behind the stage opening and for automatically restoring it to its extended dimension when returned to view.

35. In a theater, a stage opening, a collapsible preassembled stage setting, means to shift the stage setting laterally relatively to the stage opening, and means operating with the shifting means for automatically extending the stage setting when behind the stage opening and for collapsing it into a space of less horizontal dimension than the length of the setting when removed from behind the stage opening.

36. In a theater, a stage opening, wings at the sides of the stage opening narrower than the length of the stage opening, two collapsible stage settings connected together in tandem, each having a length substantially equal to the length of the stage opening, means to shift the stage settings laterally relative to the stage opening, and means operating with the shifting means for automatically extending the stage setting when behind the stage opening, and for collapsing the other stage setting into said narrower wing space.

Signed at New York, county of New York, and State of New York, this 14th day of September, 1928.

JACK POTTER STOCKTON.
